[57] ABSTRACT

The present invention is a built-up pump for bicycles. The pump consists of a tank provided with a hose, a cylinder which can be placed in the tank, when not used, or extended above the tank, when used, a piston rod which has a piston on the lower end and can accommodate the hose in its hollow portion. A handle is capable of being fit onto the outside of the tank, when not used, and used as a handle to operate the piston rod.

1 Claim, 2 Drawing Figures

PATENTED JUN 25 1974

3,819,302

FIG. 1

FIG. 2

PUMP PARTICULARLY FOR BICYCLES

The present invention relates to a built-up air pump particularly for bicycles. The built-up air pump is equipped with a tank, and reduced in size compactly, when not used.

The present invention is a built-up pump comprising a tank provided attachably and detachably with a hose, a cylinder provided with a check valve at the lower end and accommodated in the tank or fixed extendedly above the tank, a hollow piston rod equipped on the lower end with a piston sliding inside the cylinder and capable of accommodating the hose, and a handle having an inside diameter and capable of being fit to the outside of the tank and formed like a cup with an opening at one end and mountable detachably to the upper end of the piston rod.

With these and other objects in view which will become apparent in the following detailed description, the present invention will be clearly understood in connection with the accompanying drawing, in which:

FIG. 1 is an axial cross-sectional view of an air pump, designed in accordance with the present invention, in its operative position; and

FIG. 2 is a partly axial cross-sectional view of the pump, shown in its collapsed position.

Referring now to the drawing, the present invention relates to a built-up air pump, useful as an air pump, particularly for bicycles, and equipped with a tank 9 and contained compactly for the convenience of transportation, entirely avoiding inconveniences when in its inoperative position.

The built-up pump designed in accordance with the present invention, comprises a tank 9, which is equipped attachably and detachably, respectively, with a hose 7 on the lower end portion. A cylinder 3 is provided with a check valve 6 on its lower end and disposed inside the tank 9 or fixable extendedly at the upper end of the tank 9. A piston 4 slides inside the cylinder 3 at its lower end. A hollow piston rod 2 is capable of receiving the hose 7, and a handle 1 has an inside diameter which fits the outside diameter of the tank 9 and forms like a cup with an opening at one end and is mounted detachably to the upper end of the piston rod 2.

Referring now again to the drawing, a seal 8 is provided, which is attached to the hollow end formation 12 formed by the lower end of the cylinder 3 and to the in-

ternal wall of the tank 9, providing an air sealing at the part where the hollow end portion 12 is provided. A treadle 10 is swingably mounted on a stand 11 fixed at the lower end of the tank 9. The upper end opening 13 is provided inside with threads of the tank 9 and screwed onto the hollow end portion 12 of the cylinder 3. A spring 14 presses the check valve 6 to its closing position. A seat 5 for fixing the seal is fixed integrally into the hollow end portion 12. The handle 1 is screwed to or mounted by an engaging member to the upper end of the piston rod 2 perpendicularly thereto.

In operation, the cylinder 3, receiving the piston rod 2, is extendedly connected to the upper end of the tank 9 and the handle 1 is secured to the upper end of the piston rod 2, as shown in FIG. 1. The tank 9 acts as a pressure chamber, facilitating the air pumping operation. Although this pump is equipped with a tank, when it is not necessary, the cylinder 3 is inserted into the tank 9, the hose 7 is then connected with the hollow piston rod 2, and the handle 1 fits to the outside face of the tank from above as shown in FIG. 2, so that the whole equipment is reduced to a small size slightly longer than the tank 9. Accordingly, the pump is accommodated to a small reduced size, when not in use, thus very convenient for transportation and practically very useful.

While I have disclosed one embodiment of the present invention, it is to be understood that this embodiment is given by example only and not in a limiting sense.

I claim:

1. A pump comprising a tank having removably attached thereto a hose at its free end, a cylinder provided with a check valve at its lower end and sealingly received by and axially movable in said tank, a hollow piston rod having a piston reciprocating in said cylinder, a hollow cylindrical handle removably secured to the upper free end of said piston rod and having an inner diameter complementary to the outer diameter of said tank, in order to slide said handle in a coaxial arrangement in its inoperative position, and said handle having a substantially cylindrical opening receiving the free end of said piston rod in the inoperative position of said pump.

UNITED STATES PATENT OFFICE
CERTIFICATE OF CORRECTION

3,819,302

Patent No. _____

Dated June 25, 1974

Inventor(s) Isao Ohashi

It is certified that error appears in the above-identified patent
and that said Letters Patent are hereby corrected as shown below:

On the cover sheet, Item [30] , "47-57745" should
read - 57 745 / 72 --.

Signed and sealed this 1st day of October 1974.
